(57) **CLAIM**

The ornamental design for a kit for an inserting clamp with cord protector, as shown and described.

DESCRIPTION

FIG. 1 is a front perspective view of a kit for an inserting clamp with cord protector showing my new design;

FIG. 2 is a front elevational view thereof;

FIG. 3 is a rear elevational view thereof;

FIG. 4 is a top view thereof;

FIG. 5 is a bottom view thereof;

FIG. 6 is a left side elevational view thereof; and,

FIG. 7 is an environmental perspective of the kit for an inserting clamp with cord protector while in use. The broken line showing of wires in FIG. 7 is for illustrative purposes only and forms no part of the claimed design.
